UNITED STATES PATENT OFFICE.

FRANK H. ARMSTRONG, OF AUBURN, NEW YORK, ASSIGNOR TO CORONA TYPEWRITER COMPANY, INC., OF GROTON, NEW YORK, A CORPORATION OF NEW YORK.

TYPEWRITING MACHINE.

Application filed November 9, 1918. Serial No. 261,851.

To all whom it may concern:

Be it known that I, FRANK H. ARMSTRONG, a citizen of the United States of America, and a resident of Auburn, county 5 of Cayuga, State of New York, have invented certain new and useful Improvements in Typewriting Machines, of which the following is a full and clear specification.

10 This invention has relation to that type of paper-feeding devices covered in my co-pending application Serial No. 256,195, filed September 30, 1918, and the object of the present improvements is to provide a simple 15 and easily-manufactured mechanism for normally pressing the two paper-feed-frames toward the platen, as more fully hereinafter set forth.

In the drawings—

20 Fig. 1 is a perspective view of a platen-carriage, the platen-roller and one end-flange being broken away;

Fig. 2 is a longitudinal sectional view taken through one end of the carriage;

25 Fig. 3 is a plan view of Fig. 2, the platen-roller being omitted, and part of the rock-shaft being broken away;

30 Figs. 4, 5 and 6 are detail vertical sectional views showing the manner of pivotally supporting the transverse rock-bar;

35 Figs. 7, 8 and 9 are detail views hereinafter described;

Figs. 10, 11, 12 and 13 are vertical sectional views showing the different positions 40 of the paper-feed mechanism; and

Figs. 14 and 15 are views of details hereinafter described.

Referring to the drawings annexed by reference characters, 15 designates the platen-carriage provided at each end with an up-standing flange 16 in which the ends of the shaft 17' of the platen 17 are journaled in the usual manner.

45 Extending between the end-flanges 16, the full length of the carriage, is a sheet-metal bar 18 which constitutes a rock-shaft by reason of the fact that each of its extreme ends is bent downwardly to form an ear 19, which ear is pivotally supported on a screw-pivot 20 threaded from the outside inwardly through the end-flange 16, the bar being rockable upon these pivots 20. This bar is located behind the platen and at a point about on a horizontal level with the

under face of the platen. The rear edge of 55 the bar is bent downwardly to form a longitudinal flange 21 to stiffen the rock-bar, and the front edge of this rock-bar is provided with four forwardly-extending lever-fingers 22, each of which at its extreme forward end 60 is bent downwardly and then upwardly to form a hook 23 which is open at its upper side. This rockable plate-like shaft 18 may be manually rocked by means of a cam-lever 24 pivotally mounted on platen-shaft 17' 65 close to the inner face of one of the end-flanges 16 of the carriage, the cam part of this lever being provided with two working faces 25 and 26, adapted to alternately co-operate with the upper edge of an arm 27 70 formed integral with the rock-bar 18 and bent to fit flatwise against the adjacent end 16 of the carriage so that its free forward end will lie directly under the two working faces of the cam 24, said arm 27 being 75 normally held up against one or the other of said working-faces 24 and 25 by a retractile spring 28. When the arm 27 lies against the cam-face 25, the rockable bar 18 will be in its normal position, i. e., with 80 its upper face horizontal, and the feed-rolls, as hereinafter described, will be in their normal position against the platen or the work-sheet thereon; but when the cam-lever 24 is turned to swing down the forward end 85 of the arm 27 and thus bring the other cam-face 26 into locking relation with the upper edge of the arm 27, the rockable bar 18 will have its forward edge tilted downwardly and thus, in the manner hereinafter set forth, cause the feed-rolls to be retracted 90 from working position.

The feed-rolls 29 are arranged in two sets, one at each side of the mid-length of the platen. Each set consists of a front-shaft 95 30 and a corresponding rear-shaft 31, each shaft carrying one or more of the feed-rolls 29, two being shown on each shaft in the present structure, a loose spacing-sleeve 32 being arranged between each pair to space 100 them apart. Each of the front-shafts 30 is journaled loosely in upstanding ears 33 formed integral on the forward ends of a pair of flat bars 34, and each of the rear-shafts 31 has each of its ends journaled in a pair of upstanding ears 35 formed integrally with the rear end of each of the bars 34, so that each set of rolls forms a substan-

tially rectangular frame consisting of a front-shaft 30, a rear-shaft 31; and the two bars 34 which connect corresponding ends of said shafts. The rear ends of the bars 34 are so located that when the fingers 22 are depressed the lower rounded ends of hooks 23 bear downwardly upon the rear ends of the bars 34 and thus tilt said bars downwardly. In its preferred form, which is 10 that illustrated, I arrange the bent ends of the fingers 22 so that each will lie between a pair of the ears 35 in such position that the shaft 31 will extend through the hook-like part 23 of the finger, the purpose in 15 turning up the extreme end of the finger to form said hook being to engage the front face of the shaft 31 and thus assist in holding the parts in their assembled relation.

To assist in holding the shafts 31 against 20 undue endwise movement in their supporting ears 35, I provide the bar 18 with forwardly-extending fingers 36 which are bent downwardly at their forward ends to lie in axial alinement with said shafts, a slight 25 distance from the ends of said shafts. In the present construction, these shafts 31 need only be journaled loosely in the ears 35 so that they will naturally have a slight endwise movement in these ears; it is for this 30 reason that I provide said stop-lugs 36. In this way, I avoid the necessity of providing the shafts 31 with stop-collars adapted to abut against the ears 35. For the same reason, I provide each of the forward ends of 35 the bars 34 with an upstanding stop-lug 37 in position to restrict the endwise movement of the front-shafts 30. The foregoing parts are constructed and arranged substantially as in my aforesaid copending application.

40 Each of the rectangular frames, of which parts 34 form the end bars, is supported upon the flat outer ends of sheet-metal arms 38, these arms being formed integral with and extending in opposite directions at right 45 angles to flat bars 39 pivotally mounted upon the upper face of the platen-carriage, these two bars 39 extending transversely of the carriage and lying parallel with each other. The front ends of the bars 39 are 50 provided with forwardly-projecting integral pivots 40 which work in ears 41 struck up from the bottom-plate of the platen-carriage; and the rear end of each bar 39 is 55 pivotally connected to the platen-carriage by a lug 42 stamped up from the platen-carriage plate and including upwardly and laterally therefrom to form an open crotch. These two lugs 42 extend in opposite directions, that is, toward the respective ends of 60 the platen-carriage, and the rear ends of the bars 39 are normally held in the crotches formed by these lugs by means of a coil-spring 43, whereby it will be unnecessary to employ closed pivot-holding ears at these 65 rear ends of the bars 39, thereby contribut-

ing not only to cheapness of manufacture but also to ease of assembling the parts.

The spring 43 is connected to the bars 39 by means of upstanding rock arms 44 provided with notches in their vertical edges 70 to receive the hooked ends of the spring, these notches being duplicated along the said vertical edges to enable the spring to be adjusted bodily inwardly and outwardly on these arms to thereby vary the tension 75 of the spring. The upstanding rock arms 44 are connected to the bars 39 at a distance from their pivotal-points in the lugs 42, this offsetting of the arms 34 being obtained by mounting the same on the outer ends of 80 laterally-extending arms 45' formed integral with the rear ends of bars 39. To prevent undue endwise movement of the bars 39 rearwardly, each bar is provided along its inner edge with a stop-lug 46' which is 85 adapted to abut against the front edge of the adjacent pivot lug 42. It will be observed that with this simple arrangement for normally pressing the feed-roll-frames against the platen, the opposite ends of the frame 90 will be pressed toward the platen with equal tension, and that each feed-roll-frame will be entirely independent of the other frame. It will thus be seen that when the rock-shaft 18 is rocked to a position in which its 95 upper face is in horizontal position, the fingers 22 will be in their raised position and the two roller-sets will be free to be pressed up against the platen through the medium of the arms 38 and their spring-actuated 100 connections; and that when said bar 18 is rocked by swinging arm 27 downward in the manner heretofore described the downwardly-bent ends of the fingers 22 will 105 strike against the rear end of all the bars 34 and first swing them downward about the front feed-roll-shaft far enough to retract the rear feed-rolls 29 but still leave the front feed-rolls in working position. A 110 further depression of the fingers 22 will swing the bars 34 downwardly about the axis of rock-shaft 18 (and thus bring about a corresponding depression of the forward ends of the bars 34) by the following means: Several (preferably 4) of the ears 35 are 115 each extended upwardly and rearwardly to a point above the upper flat surface of the rock-bar 18, thus forming hook-like rock arms 45. The initial rocking of the rock-bar 18 and the bars 34 brings the rear extremities of the arms 45 into contact with said rock-bar 18 so that after the rear feed-rolls have been retracted from the platen these arms 45 interlock with the rock-bar 18 in the manner of a knuckle-joint and thereby cause the further rocking of the rock-bar 18 to swing the bars 34 with the rock-bar, as shown in Fig. 13, in which position both springs 43 are extended to maximum and the angular rocking members 38, 120 125 130

39 are pressed down flatwise against the upper surface of the platen-carriage 15. The parts are locked in this off position by means of the cam-face 26 of the cam-lever 5 hereinbefore described; and when the handle-end of the cam-lever is moved rearwardly, as shown in full lines in Fig. 14, to bring the other cam-face 25 into action, the spring 28 will draw the rock-bar 18 to 10 normal position and thus permit the springs 43 and the pairs of angular rocking members to restore all the feed-rolls to working position. The bars 34 have loose rocking connections with arms 38 and the angular 15 supporting members are gradually depressed by said bars to positions flat upon the base of the carriage as the shaft 18 is rocked in a direction to cast-off the feed rolls.

20 It will be observed that the outer extremities of the arms 38 are bent downwardly at 38' to pass under the bars 34 and that at points coincident with these bent down ends the platen-carriage is provided 25 with holes 51 to permit these bent ends to pass down through the top-plate of the platen-carriage when the bars 38 are depressed to their lowermost position; in this way, compactness in my device is further 30 provided for.

The sheet-metal paper-guide pan 52 is provided at its forward edge with depending ears 53 which are rigidly fastened to the rear face of the scale-bar 54. The 35 paper-guide is provided at intervals with longitudinal slots 55 through which the feed-rolls extend, and, for the purpose of ensuring a positive movement up and down of the guide in unison with the feed-rolls, 40 I provide the guide at each end with a depending ear 56 for engagement with the adjacent front feed-roll shaft 30, said ear being provided with a hole through which the shaft extends.

45 The pivotal connection of the roll frames with the rock shaft 18 and the vertical play of the rear feed-roll shafts permitted by the space between the shafts and the bottoms of hooks 23 and the space between the bottoms of hooks 23 and bars 34, permit independent movement of the feed-roll frames bodily up and down, and also permit either the front or rear edge of either of the frames to swing away from the platen, while the rock shaft is in normal position, as more fully set forth in my application before referred to. As either of the angular supporting members may swing independently of its companion member, it will be obvious 55 that either end of either frame may swing away from the platen.

The nature and scope of the invention having been thus indicated and its preferred embodiment having been specifically described, what is claimed as new is:

1. In a typewriting machine, the combination of a platen carriage, a platen rotatably mounted on the carriage, a feed-roll frame, tandem feed-rolls mounted in the frame, and a pair of spring-urged members engaging 70 opposite ends of the frame and pivotally mounted on the platen carriage to swing about axes extending transversely of the platen.

2. In a typewriting machine, the combination of a platen carriage, a platen rotatably mounted on the carriage, a feed-roll frame, tandem feed-rolls mounted in the frame, means for positively shifting the frame away from the platen to cast-off the feed-rolls, a pair of rocking members mounted on the carriage and engaging the frame adjacent opposite ends of the frame, and a single spring for rocking both of said members toward the platen.

3. In a typewriting machine, the combination of a platen carriage, a platen rotatably mounted on the carriage, a feed-roll frame, tandem feed-rolls mounted in the frame, and a pair of spring-urged members mounted on the platen carriage to swing about axes extending transversely of the platen and engaging the frame adjacent opposite ends of the frame substantially midway between the tandem feed-rolls.

4. In a typewriting machine, the combination of a platen carriage, a platen rotatably mounted on the carriage, a floating feed-roll frame, tandem feed-rolls mounted in said frame, a pair of members mounted on the platen carriage to swing about axes extending transversely of the platen and exerting pressure on said frame at two longitudinally spaced points intermediate the tandem feed-rolls, and a single spring for normally swinging both of said members toward the platen.

5. In a typewriting machine the combination of a platen carriage, a platen rotatably mounted on the carriage, a feed-roll frame, tandem feed-rolls mounted in said frame, cast-off mechanism for shifting said frame toward and from the platen, connections between the cast-off mechanism and the frame for permitting a limited movement of either or both longitudinal edges of the frame toward and from the platen independently of the cast-off mechanism and restraining sidewise and endwise movements of the frame, a pair of pressure members pivotally mounted on the carriage to swing about axes extending transversely of the platen and engaging the frame adjacent opposite ends of the frame at points intermediate the tandem feed-rolls, and a single spring for forcing said members toward the platen with a uniform pressure.

6. In a typewriting machine, the combination of a platen carriage, a platen rotatably mounted on the carriage, a feed-roll frame,

5 tandem feed-rolls mounted in the frame, a pair of members extending transversely of the carriage and pivotally connected adjacent their opposite ends to the carriage and 10 each provided with an arm extending longitudinally of the carriage under the feed-roll frame, said arms extending in opposite directions and engaging the frame adjacent opposite ends of the frame, and a spring 15 connected with said members to cause said arms to exert uniform pressure on the frame.

15 7. In a typewriting machine, the combination of a platen carriage, a platen rotatably mounted on the carriage, a pair of feed-roll frames arranged end to end, tandem feed-rolls mounted in each frame, cast-off mechanism for simultaneously shifting both frames away from the platen, two pairs of rocking 20 members mounted on the carriage, the two members of each pair exerting pressure on one frame only at points adjacent opposite ends of the frame and intermediate the tandem feed-rolls in said frame, and a pair of springs each of which is connected to one pair of said members to cause each pair of members to exert a uniform pressure on the frame engaged thereby.

25 8. In a typewriting machine, the combination of a platen carriage, a platen on the carriage, a feed-roll frame on the carriage, means for forcing the frame away from the platen, a pair of members pivotally mounted on the carriage to swing about axes extending transversely of the carriage and engaging the frame adjacent opposite ends of the frame, each of said members being provided with an actuating arm, and a spring connecting said actuating arms to cause the 30 members to exert a uniform pressure at different points on the feed-roll frame.

35 9. In a paper feed mechanism, the combination of a platen, a plurality of sets of tandem feed-rolls, a plurality of pairs of pivotally supported pressure-distributing members, each of said pairs of members cooperating with a different set of tandem feed-rolls to press the same toward the platen, and a plurality of springs each of which is connected with a different pair of pressure-distributing members to swing the two members connected therewith in opposite directions about their pivots toward the platen.

40 10. In a typewriting machine, the combination of a platen carriage, a platen on the carriage, a pair of tandem feed-rolls, means for rotatably supporting the rolls in spaced relation, a pair of pressure members pivotally mounted on the carriage and connected with the roll-supporting means at different points to permit independent or simultaneous movement of the rolls away from the platen and endwise tilting of the rolls relatively to the platen, and cast-off means for swinging first one and then the other of

said rolls away from the platen against action of said pressure members.

11. In a paper feed mechanism, the combination of a platen, a floating feed-roll frame, tandem feed-rolls in the frame, a pair of pivotally supported members on which said frame is mounted to tilt at either end or either longitudinal edge away from the platen, and a spring connected with both of said members to normally rock said members in opposite directions about their pivots to press the frame toward the platen.

15 12. In a paper feed mechanism, the combination of a platen, a feed-roll frame, tandem feed-rolls in the frame, a pair of oppositely swinging pivotally supported members engaging said frame at spaced points, a coiled spring, and means for detachably connecting opposite ends of said spring to said members at either of a plurality of points to vary the pull of the spring thereon.

20 13. In a paper feed mechanism, the combination of a pair of pivotally supported members, a coil spring connected at its ends with said members to normally swing the members in opposite directions about their pivots, and a feed-roll frame having tandem feed rolls thereon and loosely supported directly on said members intermediate the tandem feed-rolls at points spaced apart longitudinally of the rolls.

25 14. In a paper feed mechanism, the combination of a platen, a feed-roll frame, tandem feed rolls on the frame, and a pair of spring-urged pivotally supported members on which said frame is mounted at spaced aligned points to move away from the platen against the pressure of either or both members and to rock on said members about an axis extending transversely of the pivotal axes of said members through the points of connection of the members with the frame.

30 15. In a paper feed mechanism, the combination of a pair of tandem feed-roll shafts, feed rolls on said shafts, a platen, a pair of pressure members each pivotally mounted to swing about an axis extending transversely of the platen, means connected with both shafts at points spaced apart longitudinally of the shafts and supported on said members to rock about an axis extending longitudinally of the shafts and intermediate said shafts, and spring means for normally rocking said members in opposite directions about their pivots toward the platen.

35 16. In a paper feed mechanism, the combination of a platen, a plurality of feed-roll frames, tandem feed-rolls in each frame, a plurality of springs, and means interposed between each spring and a different one of said frames for independently yieldably pressing opposite ends of its associated frame toward the platen, each of said frames being tiltably mounted on its associated spring pressed means to rock thereon about

an axis extending longitudinally of the frame substantially midway between the tandem feed-rolls.

17. In a paper feed mechanism, the combination of a platen, a plurality of feed-roll frames, feed-rolls in said frames, a plurality of pairs of oppositely swinging members, each of said pairs of members loosely engaging a different frame adjacent opposite ends of the frame, and independent springs connecting the pairs of members, each of said springs normally swinging the two members connected therewith in opposite directions about their pivots toward the platen.

18. In a paper feed mechanism, the combination of a platen, a plurality of feed-roll frames, feed-rolls in the frames, a plurality of pairs of oppositely swinging members, each of said pairs of members loosely engaging a different frame adjacent opposite ends of the frame, independent springs connecting the pairs of members, each of said springs normally swinging the two members connected therewith in opposite directions about their pivots toward the platen, tions about their pivots toward the platen, and cast-off means for simultaneously forcing the frames away from the platen having direct lost-motion connections with the frames permitting the frames to yield relatively to the platen independently of movement of the cast-off means.

19. In a paper-feed mechanism, the combination of a platen, a plurality of pairs of swinging members, a plurality of springs each normally urging one pair of said members toward the platen, a plurality of feed roll frames each resting loosely on one pair of said swinging members adjacent opposite ends of the frame, a set of tandem feed-rolls in each frame, and rockable means connected with all of said frames for first tilting the frames on said swinging members about the axes of the forward feed rolls and then swinging the frames bodily about the axis of oscillation of said rockable means.

This specification signed this sixth day of November, A. D. 1918.

FRANK H. ARMSTRONG.
